COMBINATION COMB AND BRUSH

Filed March 20, 1931

INVENTOR
A. Pross

BY HIS ATTORNEY *J. Ledermann*

UNITED STATES PATENT OFFICE

ALBERT PROSS, OF BRONX, NEW YORK

COMBINATION COMB AND BRUSH

Application filed March 20, 1931. Serial No. 523,985.

The main object of this invention is to provide a hair brush to which combs may be attached in a convenient manner so that the user of the device may brush and comb the hair with a minimum of inconvenience.

Another object of the invention is to provide a hair brush which is so constructed that combs may be attached thereto and in addition has a wetting sponge which may be so adjusted as to operate with any one of the combs of the device.

The above and other objects will become apparent in the description below in which characters of reference refer to like-named parts in the drawings.

Referring briefly to the drawings, Figure 1 is a top plan view of the hair brush showing the combs attached thereto.

Figure 2 is a side elevational view of Figure 1.

Figure 3 is an end elevational view of Figure 1.

Referring in detail to the drawings, the numeral 10 indicates the back or body of the hair brush. This body has groups of bristles 11 projecting side wise therefrom. The upper surface of the back 10 of the hair brush has a rectangular block 12 mounted thereon. The longitudinal sides of this block have dove tailed slots 13 formed therein into which the dove tailed tongues 14 of the comb members 15 and 16 are adapted to be slid. A wetting sponge is adapted to cooperate with either one of these combs 15 or 16 accordingly as the position of the sponge is adjusted. The sponge or wetting element 17 is substantially longitudinal in shape and is wrapped about a connecting bar 18 from which legs 19 extend. The extremities 21 of these legs 19 are pivotally anchored in eyelets 20. The pivotal mounting of these leg extremities 21 permits the swinging through an arc of 180° of the sponge 17 from one side of the block to the opposite side.

Locking plates 22 and 23 are mounted upon

the surface of the block 12. These locking plates have offset fingers 24 which are adapted to slip over the surface of the legs 19 to retain the sponge in secure position upon either one of the combs 15 or 16. The locking plates 22 are provided with slots 25 which serve as guides and receive screws or other limiting members, said screws or studs being indicated by the numeral 26. The block 12 has lugs 27 extending upwardly through a channel 28 located in the locking plates 22. This lug 27 serves as a support for a spring 29 which has its opposite end resting upon an extension 30 of each locking plate.

This device aims to combine all three of these necessary utilities into a single member. The combs 15 and 16 are provided with dove tailed tongues to permit the ready mounting of the comb members upon the block 12 of the device. The wetting element 17 comprises a sponge or other liquid absorbing medium which rests upon the comb which selectively rests on top of either one of the comb members 15 and 16. Selectivity of this sponge member is provided by pivoting the frame holding the sponge member 17 in eyelets 20. By grasping the finger braces 31 and urging these members toward each other the locking plates 22 are released from engagement with the legs 19 of the wetting sponge frame and the latter is then permitted to rotate to a position where the sponge will rest upon the top of one or the other of the comb members 15 and 16 at the base of the slits between the teeth of the comb. When the frame has been adjusted to the desired position pressure upon members 31 of the locking plates 22 is released and members 24 will thereafter engage the legs 19 of the sponge frame and retain this frame in locked position so that the sponge will not shift from its desired location.

It is to be noted that certain changes in form and construction may be made without

departing from the spirit and scope of the invention.

I claim:

1. In a device of the class described, a hair brush, a block on said hair brush, combs, means on said block for securing said combs to said block, a hair moistening sponge pivoted on said block and means for locking said hair moistening sponge upon any of said combs.
2. In a device of the class described, a hair brush, a block on said hair brush, combs, said block having dove tailed channels therein, means on said combs for engaging in said dove tailed channels to retain said combs rigid with said block, a hair moistening sponge pivoted on said block and means for locking said hair moistening sponge upon any of said combs.
3. In a device of the class described, a hair brush, a block on said hair brush, combs, said block having dove tailed channels therein, dove tailed ridges on said combs registering in said dove tailed channels of said block for securing said combs to said block, a hair moistening sponge pivoted on said block and means for locking said hair moistening sponge upon any of said combs.
4. In a device of the class described, a hair brush, a block on said hair brush, combs, said block having dove tailed channels therein, dove tailed ridges on said combs registering in said dove tailed channels of said block for securing said combs to said block, a hair moistening sponge pivoted on said block, a frame having said sponge mounted thereon, said frame being pivoted on said block, said sponge being adapted to swing from one side to the opposite side of said block and means for locking the sponge carrying frame in adjusted position on said block.
5. In a device of the class described, a hair brush, a block on said hair brush, combs, said block having dove tailed channels therein, dove tailed ridges on said combs registering in said dove tailed channels of said block for securing said combs to said block, a hair moistening sponge pivoted on said block, a frame having said sponge mounted thereon, said frame being pivoted on said block, said sponge being adapted to swing from one side to the opposite side of said block and locking plates slidable on said block, said block plate being adapted to engage the sponge carrying frame to lock the latter in desired position and means for projecting said locking plates in engagement with said sponge carrying frame.
6. In a device of the class described, a hair brush, a block on said hair brush, combs, said block having dove tailed channels therein, dove tailed ridges on said combs registering in said dove tailed channels of said block for securing said combs to said block, a hair moistening sponge pivoted on said block, a

frame having said sponge mounted thereon, said frame being pivoted on said block, said sponge being adapted to swing from one side to the opposite side of said block and locking plates slidable on said block, said locking plate being adapted to engage the sponge carrying frame to lock the latter in desired position, and lugs mounted on said block, said locking plates having slots therein, said slots having said lugs projecting therethrough and springs resting on said lugs and engaging said locking plates for projecting the latter into engaged position with the sponge carrying frame.

In testimony whereof I affix my signature.

ALBERT PROSS.
